DESIGN FOR A SHOE

Bernard Oswell, New York, N. Y.

Application February 9, 1937, Serial No. 67,527

Term of patent 3½ years

To all whom it may concern:

Be it known that I, Bernard Oswell, a subject of the King of Great Britain, residing in the city, county, and State of New York, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view of the shoe as shown in Fig. 1.

My design is characterized by the colored welt on the sole portion of the shoe.

I claim:

The ornamental design for a shoe substantially as shown and described.

BERNARD OSWELL.
